UNITED STATES PATENT OFFICE

JAMES C. BATTLE, OF DETROIT, MICHIGAN.

LAMINATED GEAR-WHEEL.

1,247,922.

Specification of Letters Patent. Patented Nov. 27, 1917.

Application filed March 10, 1917. Serial No. 153,961.

To all whom it may concern:

Be it known that I, JAMES C. BATTLE, a citizen of the United States, and a resident of Detroit, in the county of Wayne and State of Michigan, have invented a certain new and useful Improvement in Laminated Gear-Wheels, of which the following is a specification.

The present invention relates to gear wheels, and has for an object to provide an improved gear wheel which may be made up of a number of disks or laminæ according to the size of the gear wheel required, and the strain to be placed on the gear wheel.

An object of the present invention is to provide a gear wheel of relatively light weight as compared with the width and diameter of the gear wheel, and to provide a wheel of this character which may be made entirely by means of punch-press dies, in a single, or several successive operations.

A further object of the present invention is to provide a gear wheel which may be of the internal type, which may be of the compound internal external type, or which may be of the hob type, all of which may be made by punch-press dies.

The above, and various other objects and advantages of this invention will be in part understood, and in part described, from the following detailed description of the present preferred embodiment, the same being illustrated in the accompanying drawing wherein:

Figure 1 is a side elevation of a spur gear constructed according to the present invention.

Fig. 2 is an edge elevation of the same. Fig. 3 is a transverse section taken through the gear wheel.

Fig. 4 is a side elevation of a gear wheel of the compound internal external type constructed according to the present invention.

Fig. 5 is a transverse section taken through the same.

Fig. 6 is a similar view disclosing a slightly modified form of the gear wheel of Fig. 1.

Fig. 7 is a side elevation of a gear wheel of the hob type constructed according to the present invention.

Fig. 8 is an edge elevation of the hob gear of Fig. 7, partly in section, disclosing the arrangement of the laminæ of which the gear wheel is constructed.

Referring to this drawing, and first to Figs. 1, 2 and 3, the gear wheel is disclosed as comprising four disks or laminæ 10, 11, 12 and 13, although it is to be understood that the gear wheel may be made up of any desired number of disks.

In the present instance, the disks or laminæ are disclosed as being of the same diameter, and having spur teeth 14 stamped in their marginal portions, and registering transversely. A plurality of rivets 15 are secured transversely through the laminæ to connect the same into a unitary body.

Certain of these disks or laminæ, such as the outer disks 10 and 13, are provided with relatively small openings 16 adapted to receive a shaft or the like upon which the gear wheel is to be supported. For ordinary use, these outer disks 10 and 13 afford an ample support for the gear wheel and are capable of withstanding the strain which is usually placed upon the same. If the gear wheel is to be locked to the shaft, a keyway 17 may be formed in the inner marginal edge of each outer disk 10 and 13 at one side thereof.

The intermediate disks or laminæ 11 and 12 are stamped or cut in substantially ring form with relatively large central openings 18 therein for the purpose of producing a relatively light gear wheel, and also for the purpose of economy in material.

As shown in Fig. 6, the shaft-receiving openings 16 may be formed centrally in the intermediate disks or laminæ 11^a and 12^a, and the outer disks 10 and 13 may be provided with a relatively large central opening 18.

In the form shown in Figs. 4 and 5, the disks or laminæ may all be provided with the external gear teeth 14, and the outer disks 10^b and 13^b provided with the relatively large central openings, and with internal spur teeth 19 at their inner marginal edges. In this construction, the intermediate disks or laminæ 11^a and 12^a are employed.

The hob gear disclosed in Figs. 7 and 8 comprises a plurality of disks or laminæ 20, disclosed as six in number, and provided at their outer marginal edges with the teeth 14 arranged in transversely staggered or offset relation, offsetting the disks or laminæ about their axes of rotation. Each two adjacent end disks are provided with relatively small shaft-receiving openings 21 therethrough, and if desired, the keyways

- 22 for locking the hob gear to a shaft or the like. The rivets 15 are employed for securing the disks or laminæ in lateral contact for uniting the disks into a unitary body. The intermediate disks 20 are provided with the relatively large central openings 23 for the purpose of reducing the weight of the hob gear, and also economizing in the use of the material.
- 10 In all instances, it is preferable to construct the laminated gear wheel of sheet metal or the like, and where the thickness permits, the disks may be stamped in one operation to provide the central openings 15 therein and also the gear teeth at their marginal edges.
- It is of course understood that various changes and modifications may be made in the above specifically described embodiment 20 of this invention without departing from the spirit thereof, such changes and modifications being within the scope of the following claims.
- I claim:—
- 25 1. In a wheel, the combination of a plurality of flat disks, and means for securing the disks in lateral contact and in coaxial relation, certain of the disks having central support receiving openings therethrough 30 with keyways, and certain of the disks having relatively large central openings to reduce the weight of the wheel.
2. In a wheel, the combination of a plurality of flat disks, and means for securing the disks in lateral contact, certain of the disks having central support receiving openings therethrough, and certain other disks having relatively large central openings therethrough to reduce the weight of the 35 wheel.
3. In a gear wheel, the combination of a plurality of disks having spur teeth in their peripheral edges, and means for securing the disks in lateral contact with the teeth 40 arranged in predetermined transverse rela-
- tion, certain of the disks having cut-away central portions to provide disks of substantially ring form, and certain other disks having relatively small central registering openings therethrough for the reception of 60 a support for the gear wheel.
4. In a gear wheel, the combination of a plurality of disks formed with a punch-press die to provide teeth in the marginal edges thereof and central openings therethrough, certain of the disks being provided with relatively small support-receiving openings, and certain other disks being provided with relatively large weight-reducing openings, and rivets secured transversely 65 through said disks to secure the same in lateral contact into a unitary structure.
5. A compound internal external gear wheel comprising a plurality of die-cut sheet metal disks or laminæ having central openings therethrough, and having transversely alining gear teeth in their marginal outer edges, certain of said disks having relatively small openings for receiving therethrough a support for the wheel, and certain other disks having relatively large openings for reducing the weight of the wheel, said disks with relatively large openings being provided with internal gear teeth in their inner marginal edges, and means for securing 70 said disks in lateral contact.
6. A compound internal external gear wheel comprising a plurality of disks cut to provide gear teeth in their outer marginal edges, the intermediate disks being formed with relatively small support-receiving openings therethrough, and the outer disks having relatively large weight-reducing openings formed centrally therethrough, 75 said outer disks being provided at their inner marginal edges with internal gear teeth, and means for securing said disks in lateral contact into a unitary body.

JAMES C. BATTLE.
